COMBINED IGNITION AND STARTER SWITCH

William A. Heidman, Jr., Grand Rapids, Mich.

Application June 5, 1947, Serial No. 752,645

11 Claims. (Cl. 200—4)

1

This invention relates to improvements in a combined ignition and starter switch.

The principal objects of this invention are:

First, to provide a combined ignition and starter switch for automobiles of simplified design and construction and having simplified operating characteristics.

Second, to provide a combined switch and lock assembly which is operative in its unlocked position to energize the ignition circuit of an engine and movable axially to energize the starter circuit of the engine.

Third, to provide a combined lock and switch assembly in which the lock member is rotated from a locked position by a key to energize the ignition circuit of an engine and movable axially against spring pressure when in unlocked position by pushing on the key to energize the starter circuit of the engine.

Fourth, to provide a combined lock and switch assembly for energizing the ignition and starter circuits of an engine in which the starter and ignition circuits may not be closed without the use of a key and in which the key may not be removed from the lock without first de-energizing both the starter and ignition circuits.

Fifth, to provide a highly practical lock and switch assembly for simplifying the locking and starting of an internal combustion engine.

Other objects and advantages relating to the details and economies of the invention will be apparent from the following description and claims.

The drawings, of which there is one sheet, illustrate a preferred form of my lock and switch assembly and one modified form of switch member for use therein.

Fig. 1 is a side elevational view partially broken away in cross section along the line 1—1 in Fig. 2 and showing my lock and switch in position to energize the ignition circuit and de-energize the starter circuit of an automobile engine.

Fig. 2 is a rear elevational view of the switch assembly shown in Fig. 1.

Fig. 3 is a fragmentary side elevational view similar to Fig. 1 and showing the switch actuated to energize the starter circuit, the electrical circuits associated with the switch being shown conventionally.

Fig. 4 is a front elevational view of the lock housing employed in my assembly.

Fig. 5 is a cross sectional view along the line 5—5 in Fig. 4.

Fig. 6 is a rear elevational view of the lock cylinder employed in my switch assembly.

Fig. 7 is a side elevational view of the lock cylinder shown in Fig. 6.

Fig. 8 is a front elevational view of the lock cylinder with the key removed.

Fig. 9 is a cross sectional view of a modified

2

form of switch member for use in switch assembly.

My lock and switch assembly consists generally of a lock housing 1 the rear end of which is flanged as at 2 to be attached to a cup-shaped switch housing 3. The lock housing is provided with transversely extending ears 4 apertured as at 5 to pass bolts for securing the assembly to the instrument panel of an engine and is arranged to receive a lock cylinder 6 shown in detail in Figs. 6, 7 and 8. The switch housing encloses an insulating terminal block 7 which is fixed to the bottom of the switch housing. The housing provides a chamber for the switch member generally indicated at 8 which is positioned between the end of the lock housing and the terminal block 7.

The terminal block 7 is made of an insulating material such as hard rubber or plastic and is provided with three electrically conducting pins 9 angularly spaced around the terminal block and extending through suitable insulating grommets 10 to the rear side of the switch housing. The forward face of the terminal block 7 is recessed in center as at 11 and a fourth pin 12 extends from the bottom of the recess through an insulating grommet to the rear face of the switch housing. Preferably the inner ends of the pins 9 are cup-shaped as illustrated to form retaining detents for contact bosses 13 pressed rearwardly from a triangular flange 14 formed on a cup-shaped contact member 15.

The switch member 8 is also made of insulating material like the terminal block and is provided with a rearwardly opening triangular recess 16 within which the forwardly turned flanges 17 of the contact member 15 are disposed. The switch member 8 carries a center supporting pin 18 which extends from the front face of the switch member into the recess 16 in the terminal member. The cup-shaped contact member 15 is slidably mounted on the center pin 18 and insulated therefrom by a suitable insulating sleeve 19. A coil spring 20 is positioned between the rear face of the switch member and the contact member to urge the contact member rearwardly. The forward face of the switch member is provided with a pair of spaced semi-cylindrical recesses 21 arranged to receive and engage mating semi-cylindrical prongs 22 formed on the rear end of the lock cylinder 6.

The pins 9 and 12 extending through the rear wall of the switch housing are provided with suitable screws or connections 13' for attachment to the electrical system of the automobile as shown in Fig. 3. One of the outer pins is connected to a conductor 23 extending to the live side of the battery 24. Another of the outer pins is connected to a conductor 25 for energizing auxiliary equipment such as a gasoline gauge 26 and the third outer pin 9 is connected by the conductor

27 to the primary coil 28 of the spark coil of the engine. The center pin 12 is connected by the conductor 29 to a relay 30 for closing the switch 31 for energizing the starter motor (not shown) of the automobile. The switch housing and lock housing are grounded by virtue of their connections to the instrument panel as is indicated at 32 in Fig. 3.

From the above description it should be apparent that when the switch member 8 is rotated to locked position by the lock cylinder as will be described presently, the contact bosses 13 will engage the insulating front surface of the terminal block 7 and no electrical connection can be made between the battery and any of the electrical equipment of the engine. When the switch member 8 is rotated to bring the contact bosses 13 into engagement with the forward ends of the pins 9 the ignition coil and auxiliary instruments such as the gasoline gauge will be energized through the cup-shaped contact member 15. The connection to the starter of the automobile is obtained by pressing axially inwardly on the lock cylinder to press the switch member 8 inwardly against the compression of the coil spring 28. Thus as is shown in Fig. 3, the center pin 18 on the switch member will project to the rear of the cup-shaped contact member 15 until it engages the forward face of the pin 12. An electrical circuit will then be completed through the relay 30 and conductor 29 to ground at 32 to energize the relay and close the switch 31 to actuate the starter motor.

The mechanism and construction of the lock housing and lock cylinder by means of which the switch member 8 is actuated is most clearly illustrated in Figs. 4 to 8. The lock housing defines an axial bore 33 arranged to have a rotatable and sliding fit with the lock cylinder 6. The bore 33 is axially grooved as at 34 to receive and engage the ward or locking bar 35 carried by the lock cylinder. The forward end of the bore 33 is radially enlarged or shouldered as at 36 throughout a fraction of its circumference to receive the radially extending prong 37 extending from one side of the lock cylinder near the forward end thereof. The function of the prong 37 and its mating shoulder 36 is to limit axial motion of the lock cylinder in the lock housing and to limit angular rotating motion of the lock cylinder in the housing by engagement between the prong and the ends of the annular shoulder 36.

The rear end of the lock cylinder 6 defines an annular retaining groove 38 arranged to engage the inwardly extending prong 39 formed near the rear end of the bore 33 in the lock housing. In order to permit entrance of the prong 39 into the groove 38 the rear end of the lock cylinder defines an arcuate notch 40 which when aligned with the prong 39 permits the lock cylinder to be moved axially in the bore 33 until the prong 39 registers with the groove 38.

In order to permit assembly of the lock cylinder in the lock housing, the radial shoulder 36 extends angularly a sufficient distance around the bore 33 to permit the prong 37 to enter the groove while the prong 39 is aligned with the notch 40. A spring pressed pin 41 is depressed by the prong 37 as the lock cylinder is inserted in the lock housing and when the lock cylinder is rotated to engage the prong 39 between the sides of the groove 38, the pin 41 springs out behind the prong 37 to prevent accidental rotation of the prong 37 and lock cylinder into a position in which the prong 39 and notch 40 are aligned. The lock

cylinder is thus securely retained in the lock housing and is rotatable therein throughout the angle between the pin 41 and the end of the arcuate shoulder 36. In order to permit axially inward motion of the lock cylinder in the lock housing 1, the wall of the bore 33 is axially grooved as at 42, the groove opening to the annular shoulder 36 and being arranged to receive the prong 37 carried on the lock cylinder. The rear end of the lock cylinder is axially grooved as at 43 to pass the prong 39 as the lock cylinder is pressed inwardly and the grooves 42 and 43 are angularly disposed with respect to the locking groove 34 so that the ward or locking bar 35 must be turned out of engagement with the groove 34 prior to axial motion of the lock cylinder.

The lock cylinder is provided with a key hole slot 44 in the forward end thereof arranged to receive a key for actuating the lock ward 35 and the key and ward are arranged in a well known manner so that the key may not be removed from the lock cylinder except when the ward is in extended or locking position. Since the ward 35 cannot be extended from the lock cylinder except when it is in registry with the locking groove 34, it is impossible to remove the key from the lock except when the lock cylinder 6 and switch member 8 are in locked position and since it is impossible to turn the switch member 8 or push the pin 18 into engagement with the pin 12 without actuating the lock cylinder, it is impossible to energize the ignition circuit or the starter of the automobile without the use of the key.

The modified form of switch member 8A illustrated in Fig. 9 is similar to the preferred form 8 with the exception that the center pin 18A does not extend completely through the switch member 8A. The contact member 15A is provided with a forwardly turned annular flange 45 which is in electrical sliding contact with the rear end of the pin 18A so that when the contact boss 13 of the contact 15A is in engagement with the live terminal 9, the live side of the battery may be connected to the relay 30 by pressing the switch member 8A and pin 18A to the rear in the same manner as in the preferred form of switch. When using the modified form of switch member, the relay 30 will naturally be connected to ground rather than to the live side of the battery.

It will be noted that my lock and switch assembly employs parts which are more or less standard in present day ignition switch locks with the addition of the center starter terminal to the switch housing and the grooves in the lock housing and lock cylinder for axial motion of the lock cylinder in the housing. The same coil spring which is presently used to obtain good electrical contact between the terminals of the ignition switch is employed to return the switch member and starter contact to de-energized position so that with very little increased cost over a standard ignition lock switch I am able to provide a lockable starter switch. By using my switch it is possible to prevent unauthorized persons or children from energizing the automobile starter and the automobile may be turned on and the engine started by the single motion of inserting the key and unlocking the ignition system and pushing in on the ignition key. My switch eliminates separate starter buttons either foot or hand operated and may be manufactured at very low cost.

I have thus described two highly practical commercial embodiments of my invention and have not attempted to show all possible modifications

thereof as such minor changes as may appear desirable should be apparent from the foregoing description. It should be apparent that various relative arrangements of the lock cylinder and housing prongs and grooves may be devised to provide the same operating characteristics as my switch. Thus the relative position of the prongs and grooves on the lock cylinder and lock housing may be reversed or the angular position on the cylinder or housing may be changed without departing from the theory of my invention. The lock and switch is applicable to automobiles, tractors, boats, airplanes and the like.

Having thus described my invention, what I claim as new and desire to secure by Letters Patent, is:

1. Lock mechanism for a combined ignition and starter switch for an automobile comprising a lock housing arranged to be secured and grounded to the instrument panel of the automobile, a lock cylinder disposed directly in said lock housing and having a driving engagement with said switch, a key operated ward on said lock cylinder engageable with said lock housing for preventing rotation of said lock cylinder, a radially extending prong on the front of said lock cylinder, said housing defining an arcuate shoulder engageable with said prong to limit axial and rotative motion of said cylinder relative to said lock housing, and an axially extending groove in said lock housing opening to said arcuate shoulder to receive said prong to permit axial motion of said lock cylinder in a single rotative position thereof to move said switch axially.

2. A combined ignition and starter switch for an engine comprising a lock housing arranged to be secured and rounded to the instrument panel of the engine, a switch housing secured to the back of said lock housing, a terminal block secured in the rear of said switch housing and having three angularly spaced terminal pins opening to the forward face thereof, said terminal pins extending through the rear of said switch housing, the forward face of said terminal block defining a recess, a center pin extending between said recess and the rear of said switch housing, an insulating disc having a triangular recess in its rear face rotatably mounted in said switch housing, a cup-shaped contact member having triangularly disposed flanges non-rotatably received in said triangular recess, a guide pin extending through said switch member and triangular recess and forming a support for said contact member, said contact member being insulated from said guide pin, three contact bosses spaced around the periphery of said contact member arranged to simultaneously engage or be disengaged from said angularly spaced pins on said terminal block by rotation of said disc, a coil spring positioned between said disc and said contact member for urging said contact member into engagement with said terminal block, a lock cylinder disposed directly in said lock housing and having a driving engagement with said disc and electrical contact with said guide pin, a radially extending prong on the front of said lock cylinder, said lock housing defining an arcuate shoulder engageable with said prong to limit axial and rotative motion of said cylinder relative to said lock housing, and an axially extending groove in said lock housing opening to said arcuate shoulder to receive said prong to permit axial motion of said lock cylinder in the unlocked rotative position thereof to move said disc and guide pin axially against the compres-

sion of said spring and to contact said lock housing with said center pin on said terminal block.

3. A combined ignition and starter switch for an automobile comprising a lock housing arranged to be secured and grounded to the automobile, a switch housing secured to said lock housing, a terminal block secured to said switch housing and having angularly spaced terminal pins opening to the forward face thereof, said terminal pins extending through the rear of said switch housing, a center pin extending between the forward face of said terminal block and the rear of said switch housing, an insulating switch member rotatably mounted in said switch housing, a contact member having a rotary driving flange engaged with said switch member, a guide pin carried by said switch member and forming a support for said contact member, contact bosses on said contact member arranged to simultaneously engage or be disengaged from said angularly spaced pins on said terminal block by rotation of said switch member, a coil spring positioned between said switch member and said contact member for urging said contact member into engagement with said terminal block, a lock cylinder disposed directly in said lock housing and having a driving engagement with said switch member, a prong on said lock cylinder, said cylinder defining an arcuate shoulder engageable with said prong to limit axial and rotative motion of said cylinder relative to said lock housing, and an axially extending groove in said lock housing opening to said arcuate shoulder to permit axial motion of said lock cylinder in a single rotative position thereof to move said switch member and guide pin axially against the compression of said spring and into contact with said center pin on said terminal block.

4. In combination with a cooperating cylinder lock and lock housing, said cylinder being rotatable directly in said housing between a locked and unlocked position, a switch housing secured to said lock housing and having a terminal block therein, a plurality of terminals angularly spaced around said terminal block and extending through said switch housing, an insulating disc positioned in said switch housing between said terminal block and lock housing and having a direct driving engagement with said cylinder, a metallic contact member carried by said disc and having contact bosses arranged to be rotated with said disc into and out of engagement with said terminals, a guide pin carried by said disc and supporting said contact member for sliding motion relative to said disc, a coil spring positioned between said contact member and disc, and a starter terminal carried by said terminal block and extending through said switch housing, said starter terminal being engageable with said guide pin upon axial motion of said cylinder and disc against the compression of said spring, said lock cylinder and lock housing having cooperative prongs and grooves arranged to permit axial motion of said lock cylinder in the unlocked position thereof and prevent axial movement in all other positions thereof.

5. In combination with a cooperating lock cylinder and lock housing, said cylinder being key operated and rotatable directly in said housing between a locked and unlocked position, a switch comprising a housing secured directly to said lock housing, a terminal block in said switch housing, circularly arranged terminals mounted on said terminal block, an insulating switch member positioned between said terminal block and

said lock cylinder and having a direct driving engagement with said lock cylinder, a guide member carried by said switch member and extending therethrough into electrical engagement with said lock cylinder, a contact member carried on said guide member for axial sliding motion with respect thereto, said contact member being insulated from said guide member and having a driving engagement with said switch member for rotation therewith into and out of engagement with said terminals, a spring positioned between said switch member and contact member urging said contact member toward said terminals, and a starter terminal carried by said terminal block centrally thereof and engageable with said guide member upon axial motion of said switch member and guide member against the compression of said spring, said lock cylinder and lock housing having cooperative prong and groove portions permitting axial motion of said lock cylinder only in the unlocked position of said cylinder.

6. In combination with a lock cylinder and lock housing, said cylinder being key operated and rotatable directly in said housing between a locked and unlocked position and movable axially of said housing only in the unlocked position thereof, a combined ignition and starter switch comprising a switch housing secured directly to said lock housing and having ignition and starter terminals therein, an insulating switch member having a direct driving engagement with said lock cylinder, a spring urging said switch member into engagement with said lock cylinder, a first contact member rotatable with said switch member for engaging said ignition terminals but movable axially relative to said switch member, and a contact pin member rigidly carried by said switch member and engageable with said starter terminal upon axial motion of said lock cylinder and switch member, said contact pin extending through said first contact member and forming a supporting guide therefor.

7. In combination with a lock cylinder and lock housing, said cylinder being key operated and rotatable directly in said housing between a locked and unlocked position and movable axially of said housing only in the unlocked position thereof, a combined ignition and starter switch comprising a switch housing secured directly to said lock housing and having ignition and starter terminals therein, a contact member having a driving engagement with said lock cylinder, a spring compressed between said contact member and said lock cylinder, and a second contact member extending through said first contact member and engageable between said starter terminal and lock cylinder upon axial motion of said lock cylinder and second contact member.

8. In combination with a cooperative lock cylinder and lock housing, said cylinder being key operated between a locked and unlocked position and arranged to hold the key therein in the unlocked position thereof, a switch comprising a terminal block, angularly arranged ignition terminals mounted on said terminal block, an insulating switch member positioned between said terminal block and said lock cylinder and having a direct driving engagement with said lock cylinder, a contact member carried on said switch member for rotation therewith into and out of engagement with said terminals, a spring positioned between said switch member and contact member for urging said contact member toward said terminals, a starter contact rigidly carried

by said switch member, and a starter terminal carried by said terminal block engageable with said starter contact upon axial motion of said switch member, said lock cylinder and lock housing having cooperative prong and groove portions permitting axial motion of said lock cylinder in the unlocked position of said cylinder.

9. A combined ignition and starter lock and switch comprising a lock having a cylinder key operated between a locked and unlocked position, said cylinder being arranged to retain said key in the unlocked position thereof, a terminal block having ignition and starter terminals thereon, an insulating switch member having ignition and starter contacts thereon and having a driving engagement with said cylinder, said ignition contacts being slidably axially relative to said switch member, said switch member being rotatable to engage said ignition contacts with said ignition terminals and axially movable to engage said starter contact with said starter terminal, and a spring opposing relative axial motion of said switch member and ignition contacts, said cylinder being axially movable in the unlocked position thereof against the compression of said spring to move said switch member axially.

10. A combined ignition and starter lock and switch comprising a lock having a cylinder key operated between a locked and unlocked position, a terminal block having ignition terminals arranged around its periphery and a center starter terminal extending therethrough, an insulating switch member having a center starter contact thereon and having a driving engagement with said cylinder, a metal stamping slidably mounted on said starter contact and having rotary driving engagement with said switch member, ignition contacts formed on said stamping, said switch member being rotatable to engage said ignition contacts with said ignition terminals and axially movable to engage said starter contact with said starter terminal, and a spring positioned between said stamping and said switch member opposing axial motion of said switch member, said cylinder being axially movable only in the unlocked position thereof against the compression of said spring to move said switch member axially.

11. Lock mechanism for a combined ignition and starter switch for an automobile comprising a lock housing arranged to be secured and grounded to the instrument panel of the automobile, a lock cylinder disposed directly in said lock housing and having a driving engagement with said switch, a key operated ward on said lock cylinder engageable with said lock housing for preventing rotation of said lock cylinder, a radially extending projection on said lock cylinder, said housing defining an arcuate shoulder engageable with said projection to limit rotative motion of said cylinder relative to said lock housing, and an axially extending groove formed in said lock housing and opening to said shoulder to receive said projection and permit axial motion of said lock cylinder in a single rotative position thereof to move said switch axially.
